CLAIM

The ornamental design for a handheld phototherapy device, as shown and described.

DESCRIPTION

FIG. 1 illustrates a top perspective view of a handheld phototherapy device;

FIG. 2 illustrates a front view of the handheld phototherapy device thereof;

FIG. 3 illustrates a back view of the handheld phototherapy device thereof;

FIG. 4 illustrates a left side view of the handheld phototherapy device thereof;

FIG. 5 illustrates a right side view of the handheld phototherapy device thereof;

FIG. 6 illustrates a top view of the handheld phototherapy device thereof;

FIG. 7 illustrates a bottom view of the handheld phototherapy device thereof; and,

FIG. 8 illustrates a bottom perspective view of the handheld phototherapy device thereof.

1 Claim, 7 Drawing Sheets
